UNITED STATES PATENT OFFICE.

DAVID M. WATSON, OF ELKINS PARK, AND RUSSELL H. BOWEN, OF PHILADELPHIA, PENNSYLVANIA, ASSIGNORS TO THE AMERICAN PULLEY COMPANY, OF PHILADELPHIA, PENNSYLVANIA, A CORPORATION OF PENNSYLVANIA.

BELT-SHIFTER ATTACHMENT FOR SHAFT HANGERS.

Application filed July 2, 1924. Serial No. 723,677.

To all whom it may concern:

Be it known that we, DAVID M. WATSON, a resident of Elkins Park, in the county of Montgomery and State of Pennsylvania, and RUSSELL H. BOWEN, a resident of Philadelphia, in the county of Philadelphia and State of Pennsylvania, citizens of the United States, have invented certain new and useful Improvements in Belt-Shifters Attachments for Shaft Hangers, whereof the following is a specification, reference being had to the accompanying drawings.

This invention relates to a belt shifter means in the form of an attachment or accessory useful in connection with standard types of shaft hangers, and is directed toward improving devices of this kind, more especially with regard to rendering them easy of application to the hangers; secure against dislodgement when once in place; capable of ready adjustment to meet the varying requirements of practice and of maintaining such adjustment against disturbance from shocks and vibration; and, in general, toward securing the advantages of simplified construction, such as reliability in long continuous usage, and economy in manufacture.

From the detailed description hereinafter of a typical embodiment of our invention, will be manifest how the desideratum above outlined may be readily realized, the appended claims serving to define those features which we believe to be novel and wholly within the scope of the invention.

With reference to the drawings, Fig. I is an illustration showing our improved belt shifting attachment applied to a shaft hanger of standard construction.

Fig. II is a plan view of certain parts of the shifter attachment in assemblage.

Fig. III is a side elevation of the parts shown in Fig. II.

Fig. IV is an end view of the same looking from the right of Fig. III.

Fig. V is a section taken as indicated by the arrows V—V in Figs. I and III.

Figs. VI, VII, and VIII are separate perspective views respectively of the parts of the attachment shown in Figs. II and III; and

Fig. IX is a detail sectional view taken as indicated by the arrows IX—IX in Figs. I and III.

The hanger herein shown is of a conventional type comprising the usual complementarily angularly sloped side legs 1 that are joined at an intermediate region by a transverse tie-bar 2. The structure is further braced by an additional or auxiliary bar 3 that connects the legs 1 at a region immediately adjacent the ends which carry the feet 4 whereby the hanger may be secured to any convenient support. The interval 5 between the legs 1 below the tie-bar 2, is closed by a removable bridge piece 6; and a journal box 7 for a shaft S with pulleys P (only one of said pulleys being visible in Fig. I) mounted thereon, is accommodated within the space 5. The journal box 7 may be supported, with capacity for universal positional adjustment in the usual manner, by opposed set screws 8—8 and 9—9 extending respectively through the legs 1 and the parts 2—6. The main or body portion of the hanger comprising the legs 1 and the transverse bars 2—3, in the instance shown, is composed of two counterpart halves or sections 10 of sheet metal that are substantially of semi-circular cross section throughout, thereby to define, when in opposed relation in the assembly, a rounded configuration of the portions specifically mentioned with provision however, of an internal perimetrical or marginal fin 11. This fin 11 is enlarged or broadened somewhat at the corner regions of emergence of the tie-bar 2 with the legs 1 as shown at 12 for accommodation of rivets 13 whereby the component sections 10, 10 of the structure are permanently secured together. The hanger is reinforced internally by web plates 14, 14, a pair of these lying in the medial plane at each side of the structure, and each such pair extends diametrically across a hollow leg 1 as well as part way into the tubular tie-bar 2, as best shown in Fig. IX. Outer marginal portions of the reinforcing plates 14 are offset or joggled as shown at 15 in the latter illustration, so as to respectively overlap abutting longitudinal internal flanges 16, 16 of the opposed sections 10, 10 that compose the main portion of the hanger.

Coming now to our improved belt shifter attachment, the same will be observed to include a swivel bearing support member generally indicated by the numeral 17 in the

several illustrations, and a lever arm 18 capable of angular adjustment about a fulcrum axis that is afforded by a pivot bolt 19 carried by the bearing member. The lever arm 18 is pierced at intervals lengthwise as at 20 to permit,—as may be required in meeting the exigencies of practice,—positional changes of a slide rod 21 whereto are affixed fingers 22 for engaging the belt B which is to be shifted between the pulleys P. The bearing support 17 comprises two parts in the form of plates which are respectively designated 23, 24, and adapted to engage opposite side faces of the hanger diagonally crosswise of the angular juncture between one of the legs 1 and the tie-bar 2. More especially from Figs. VI and VII it will be observed that the plates 23, 24 are, substantially, right and left complements of one another, being oppositely concaved to accord with the surface configurations of the hanger, and each characterized by a perimetrical marginal facing 26 with correspondingly disposed recessions 27—28, the latter designed to snugly fit the cross sectional configurations respectively of the legs 1 and the cross bar 2. At coordinated points, the plates 23, 24 are cut away or notched in their faces as at 29—29 to afford clearances for the heads of the rivets 13 previously mentioned, and their diagonally opposite ear projections 30—30 are apertured, as at 31—31, for passage of clamp bolts 32—33 (see Figs. I and II) whereby the bearing support 27 is secured in position, the latter of the two bolts marked 33 occupying the crotch between the leg 1 and the tie-bar 2 at the corresponding side of the hanger. The plate 23 differs from its fellow 24 only in that it has an offset or bracket-like extension 34 which terminates in a hollow boss 35. The projecting annular face 36 of this boss 35 is radially notched as shown in Fig. VI; and the base of said hollow boss is axially pierced as at 37 to take the pivot bolt 19. The boss 38 at the fulcrum end of the lever arm 18 (see Fig. VIII), corresponds in diameter to the boss 35 of the plate 23, and has an annular face 39 indented for locking interengagement with the radial notches of said plate, as well as an axially aligned aperture 40 for the pivot bolt 19.

By virtue of the diagonal positioning of the bearing support member 17 crosswise of the juncture between a leg 1 and the tie-bar 2, and on account of the firm grip of the recessed marginal faces 27, 28 of the components 23, 24 engaging these hanger portions with a tight fit, said bearing support member 17 will obviously be rigidly held against displacement, especially in view of the allocation of the clamp bolt 33 in the juncture crotch between said hanger parts. By loosening the swivel bolt 19, the arm 18 may be angularly adjusted to suit the angle of ap-

proach of the belt B toward the pulleys P. When the desired adjustment is secured, the interfitting corrugations of the meeting boss faces 36, 39 will cooperate, upon tightening of the swivel bolt 19, to preclude the possibility of subsequent accidental movement of the arm 18.

In practice there are of course at least two belt hangers employed with the pulleys P on the shaft S disposed between them, and a shifter attachment associated with each hanger so that the slide rod 21 carrying the belt engaging fingers 22 is afforded support at both ends.

Having thus described our invention, we claim:

1. A belt shifter attachment for a shaft hanger characterized by spaced legs and a transverse tie-bar extending therebetween, said attachment including a bearing support member adapted to engage both a leg and the tie-bar of the hanger for better security against displacement, and a belt shifter rod guide arm angularly adjustable on said bearing support member.

2. A belt shifter attachment for a shaft hanger characterized by spaced legs and a transverse tie-bar extending therebetween, said attachment including a bearing support member adapted to be secured diagonally across the juncture of one of the hanger legs and the tie-bar for better security against displacement, and a belt shifter rod guide arm angularly adjustable on said bearing support member.

3. A belt shifter attachment for a shaft hanger characterized by spaced legs and a transverse tie-bar extending therebetween, said attachment including a bearing support member constituted by clamp plates configured to snugly fit against opposite side faces of the hanger diagonally crosswise of the angular juncture between one of the hanger legs and the cross bar aforesaid, and a belt shifter rod guide arm angularly adjustable on said bearing support.

4. A belt shifter attachment for a shaft hanger characterized by spaced legs and a transverse tie-bar extending therebetween; said attachment including a bearing support constituted by clamp plates adapted to engage opposite sides of one leg, of the hanger, diagonally located bolts to clamp the plates to the hanger leg, one of said bolts occupying the crotch between said leg and the cross bar of the hanger, and a belt shifter rod guide arm angularly adjustable on said bearing support.

5. A belt shifter attachment for a shaft hanger characterized by spaced legs and a transverse tie-bar extending therebetween, said attachment including a bearing support comprising clamp plates for engaging opposite side faces to both one leg and the tie-bar of the hanger, one of said plates hav-

- ing a projecting swivel bearing boss with radial face notches, means for clamping said plates in position, an angularly adjustable belt shifter rod guide arm with a fulcrum face corrugated for locking interengagement with the notched face of the bearing boss aforesaid, and a fulcrum bolt to secure the arm in adjusted positions relative to the bearing support.
- 10 6. A belt shifter attachment for a shaft hanger characterized by spaced legs and a transverse tie-bar extending therebetween, said attachment including a bearing support member comprising clamp plates configured to snugly fit opposite side faces of the hanger diagonally crosswise of the angular juncture between one of the legs and

the cross bar aforesaid, one of said plates affording a projecting swivel bearing boss with radial face notches, an angularly adjustable belt shifter rod guide arm with a fulcrum face corrugated for locking interengagement with the notched face of the bearing boss aforesaid, and a fulcrum bolt to secure the arm in adjusted positions relative to the bearing support.

In testimony whereof, we have hereunto signed our names at Philadelphia, Pennsylvania, this 26th day of June, 1924.

DAVID M. WATSON.
RUSSELL H. BOWEN.
